RICHARD D. ANANSON, OF STIRLING, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,281,474.

Specification of Letters Patent. Patented Oct. 15, 1918.

Application filed January 31, 1917. Serial No. 145,618.

To all whom it may concern:

Be it known that I, RICHARD D. ANANSON, a citizen of the United States, and resident of Stirling, county of Morris, and State of New Jersey, have invented certain new and useful Improvements in Type-Writing Machines, of which the following is a specification, reference being had to the accompanying drawings, forming a part thereof.

10 My invention relates to typewriting machines and has special reference to such as are adapted for use in making duplicate bills or the like in connection with a series of continuous webs or strips of paper which are 15 superposed and have sheets of carbon paper, or other means for making duplicate copies, between them.

One object of my invention is to provide a simple and durable machine by means of 20 which duplicate bills or the like may be produced on a continuous web and readily cut or torn off when the typewritten matter is completed, without tearing the carbon paper or other means of like nature which is 25 used for producing the duplicate copies, and whereby the duplicating sheets may be used repeatedly until they are worn out.

Another object is to provide a machine for the aforesaid purpose which may be readily 30 adjusted to the length of the bills which are to be made out on the machine, so that after the machine is set there will be no question but what the bills will be separated from each other and from the web, along the 35 proper line of division between them.

Another object is to provide a mechanism 40 which may be applied to typewriting machines of well known types without material change, or in other words, an attachment whereby ordinary typewriters may be readily adapted for use with multiple sheet webs.

Other objects and advantages of my invention will be set forth hereinafter and my 45 invention is by no means restricted to any particular field of usefulness.

Referring to the drawings:

Figure 1 is a side elevation of a typewriting machine equipped with one embodiment 50 of my invention.

Fig. 2 is a diagrammatic view of the platen and the carbon rolls and showing the leaves of the web with the interposed carbon sheets in longitudinal section.

Fig. 3 is a transverse section taken on the 55 line 3—3 of Fig. 2.

Fig. 4 is a plan view of the machine shown in Fig. 1, with the carbon sheets partially broken away.

Fig. 5 is a partially sectional elevation 60 showing one of the carbon rolls together with the spindle on which it is mounted and the frame which supports the spindle.

A sectional detail taken on the line 6—6 of Fig. 5, is shown in Fig. 6. 65

Fig. 7 is another sectional detail showing one form of stop for holding the carbon roll actuating frame.

Fig. 8 is a sectional detail showing the clutch for releasing the platen. 70

Fig. 9 is a perspective view of a web of paper such as is suitable for use in a machine of the previous figures.

In the drawings, 10 designates the frame of a typewriter including a base 11, 12 designates the carriage, 13 the platen, and 14 the spindle to which the platen is secured. The spindle 14 is rotatively mounted in suitable bearings 15 in the carriage 12 and is provided at its respective ends with knobs 16 by which the platen may be readily turned. Mounted on the spindle 14 close to the platen is the usual spacing ratchet wheel 17. All of the parts so far mentioned are arranged in a well known manner and 75 80 85 perform their usual functions.

Extending parallel to the platen is a cutting bar 19 arranged to cut the web along the line of division between the bills. A frame 20 is attached to the carriage 12 and 90 extends backwardly from the typewriting machine as shown in Figs. 1 and 4. It is composed of side bars 21 supporting brackets 22 and transverse rods 23—24—25. The side brackets extend downwardly and carry 95 wheels or rollers 26 which are adapted to engage a rail 27 which is attached to the base 11 of the typewriter at the rear. The side bars 21 are arranged to provide bearings 28—29—30—31, two of which are 100 formed in one of the bars and two in the other in staggered relation.

Mounted in the respective bearings are spindles 32—33—34—35 of which 32 is shown on a larger scale in Fig. 5. These 105 spindles are identical and each is provided with a gear wheel or pinion 36 near one end. The spindle extension 37 beyond the pinion

is adapted to enter the bearings 28 for example, in the side bar 21 and is held in place by a latch 38 pivoted at 39 on the side bar and adapted to be swung over the extension 5 as clearly shown in Figs. 4 and 5.

The end of the spindle is preferably provided with an enlargement or flange 40 so that the spindle is held in position longitudinally by the pinion 36 and the flange 40, 10 which engage opposite sides of the side bar 21.

Each spindle is thus rotatively mounted in a single bearing and a suitable length of manifold web such as carbon paper is rolled 15 on the spindle, the webs for the respective spindles being designated 41-42-43-44. The spindles are each provided with a longitudinal clamping wire or bar 45. The ends of the clamping bar extend inwardly 20 through suitable holes in the spindle which is tubular as shown in Fig. 6. The ends of the bar are enlarged as shown at 46 and springs 47 are interposed tending to hold the clamping bar in engagement with the 25 outer surface of the spindle.

The arrangement of parts is such that the carbon web may be readily slipped under the clamping bar and held in place by this means as shown in Fig. 5. The spindle is 30 then turned to wrap the carbon web upon the spindle all of the webs being arranged to lead off either at the top or at the bottom when the spindles are mounted in place in the frame 20. For convenience it will be 35 first assumed that they are led off at the top as shown in Fig. 4.

An actuating frame 50 which is preferably rectangular in form as shown in Fig. 4, has rack teeth formed at 51 on the bottom 40 edge of its side bars which are adapted to rest upon and mesh with the pinions 36 of the spindles. The side bars are furthermore preferably graduated as shown in Fig. 1 at 52, and when the carriage is in position it 45 is adapted to be moved forth and back to concurrently actuate the spindles as hereinafter explained. It is held in place by guide rollers 53 which are mounted on brackets 54 pivoted at 55 on the side bars 50 21 of the frame 20. The arrangement of parts is such that the brackets may be swung outwardly on their pivots and the rollers disengaged from the actuating frame, permitting it to be lifted off of the pinions. 55 However, when they are in the positions shown in Figs. 1 and 4, they do not interfere with the movement of the actuating frame forth and back on the pinions but prevent it from being overbalanced or becoming disengaged from the pinions during the operation of the machine.

Rotatively mounted on a stud or projection 60 adjacent to the platen 13, is a gear wheel 61 which meshes with a co-operating gear 62 on the spindle 14 of the platen. A

spiral spring 63 is mounted upon and is connected at its inner end to the projection 60 and is connected to the gear wheel 61 at its outer end. The arrangement of parts is such that when the platen is turned as the 70 work advances from the beginning to the end of the bill or the like, the spring is wound up for the purpose hereinafter explained.

The platen may be released from the 75 spring 63 by means of a clutch 90 which is actuated by a clutch pin 91.

The gear wheel 61 has a plurality of circumferentially arranged holes 64 which are adapted to receive a pin or peg shown at 80 65 in Fig. 4.

Mounted on the spindle 14 adjacent to one of the bearings 15 is a ratchet wheel 66 with which co-operates a pawl 67. This pawl 67 is pivoted at 68 and is held in engagement with the teeth of the ratchet wheel by a spring 69. It may be released either manually or automatically, as hereinafter explained, by means of a key 70, which is pivoted at 71 and has a projection 72 extending into the path of movement of the pin 65. The arrangement of parts is such that when the pin engages the projection 72 it actuates the key and releases the pawl 67 permitting the platen 13 to be returned 95 to its initial position by the action of the spiral spring 63 which is associated with the gear wheel 61.

The actuating frame 50 is arranged to be secured in a predetermined position by 100 some suitable latch such as the latch 73 which is adapted to engage the tie rod 24 or a locking pin 74 which is adapted to engage the teeth of the rack 51.

The operation of the machine will be understood from the following description. In utilizing the machine the guide rollers 53 are first swung back on their pivots 55 and the actuating frame 50 lifted from the pinions 36, the latches 38 are next swung 110 outwardly on their pivots 39 and the spindles 32-33-34-35 removed. A suitable web 78 having a plurality of superposed layers formed by folding, as shown in Fig. 8, is drawn from a suitable supply roll (not 115 shown) at the back of the machine upwardly, as shown in broken lines at Fig. 1, over the tie rods 24 and 25 and under the platen 13, around which it is wrapped as shown in Fig. 2. The paper is held against the 120 platen by the usual means (not shown) and is in position for writing.

When the web is first started in the machine it is fed through until the line of division between the first and second bills 125 or other forms which may be printed on the web falls substantially opposite the tie rod 25 at a point designated 80 in Fig. 2. The carbon sheets 41-42-43-44, which are of suitable length and are attached to the 130

respective spindles 32—33—34—35 as already explained, are rolled up on the spindles.

The spindles are next set into the machine 5 with the extensions 37 engaging the several bearings 28—29—30—31, their unattached ends being introduced from opposite sides between the folds of the web 78. As each spindle is introduced beginning, for example, with the spindle 35, which is introduced 10 between the bottom layer and the layer next above it, its carbon sheet is drawn out from the roll between the folds until it extends to the point 80.

15 The spindle 34 is next introduced and its carbon sheet 43 spread out between the second and third folds from the bottom. In like manner the spindles 33 and 32 are introduced and their carbon sheets 42 and 41 spread between the upper layers. The spindles are secured in position by swinging the latches 38 back into place as soon as they are set in the machine and the actuating frame 50 is next mounted on the pinions 36 20 with its teeth 51 meshing therewith. The frame is held in place by the guide rollers 53 which are next swung into position.

It is evident that on the one hand, any movement of the actuating frame will produce a concurrent rotation of the spindles 32—33—34—35, and on the other hand, a movement of the web which unwinds the carbon sheets, will turn the spindles and produce a movement of the actuating frame. 35 This is what happens when the web is now fed forward by turning the platen 13 in the usual manner.

When the platen is turned so that the second bill or form on the web is in the machine, it is evident that the first bill which has no carbon or other duplicating sheets, has now passed through the machine but has not been written on. The second bill is now in position to be made out in the usual manner and as it is written out the copies will be produced on account of the interposed carbon sheets.

The pin 65 is set in one of the holes 64, depending on the length of the bill, in such 50 position that when the bill is completed the pin will engage the projection 72, actuate the key 70, and release the pawl 67, thereby permitting the platen to be returned to the position which it occupied at the beginning of the bill, by the spring 63.

The latch 67 is released and the gear 63 uncoupled from the platen by means of the clutch pin while the web is being adjusted into position to start the bill. Any other 60 suitable means for releasing the platen from the spring 63 until the web has been adjusted to this point, may be employed.

Assuming that the bill has been written, the key 70 actuated and the platen returned 65 to its initial position by the spring, the op-

erator pushes back on the actuating frame 50, thereby turning the spindles 32, 33, 34, 35 and winding up the carbon paper as the web moves backwardly. The carbon sheets and the web have now returned to the position in which the carbon sheets extend, to the point 80 in Fig. 2, this being permissible without pulling the web out of the machine, by the first blank bill which is still attached to the web although the second one is already filled out.

The actuating frame 50 is next locked or latched in position either by the latch 73 which is adapted to engage the rod 24, if the bills are of a predetermined standard 80 length for which the machine is designed, or by means of a pin 74 which is arranged to engage the teeth of the rack on the actuating frame and hold it in any position which it may be adjusted. The platen is next actuated in the usual manner to draw the web forward and since the actuating frame is locked so that the carbon sheets cannot be unrolled the web advances without the carbon sheets. This is continued for the length 90 of one bill, thereby transferring the web relative to the carbon sheets and preparing it for the next bill.

As the web is now advanced the first blank bill may be torn off by drawing it into engagement with the cutter 19. The web is then still further advanced until the end of the second bill is substantially at the point 80; then the actuating frame 50 is released and the web advanced together with 100 the carbon sheets until the third bill is ready to be written upon. When the third bill is completed the process of backing the web, holding the carbon rolls against rotation, drawing the web forward relative to the 105 carbon sheets, etc., is repeated. Thus the carbon paper is not cut off or lost and may be used repeatedly until it is worn out.

It is of course immaterial whether the actuating frame moves backward or forward when the web advances and this will depend upon whether the carbon sheets are wound on the spindles in one direction or the other; for example, if the carbon sheets are led off from the top of the roll as shown in Fig. 115 2, the spindles will rotate in a clockwise direction as the web advances and will consequently cause the actuating frame to move toward the platen. It will then be pushed back by the operation in drawing the web 120 back and winding up the carbon sheets. On the other hand, it will be moved in the reverse direction if the carbon sheets are led off from the bottom of the spindles. In the latter case the latch 73 will be located at the 125 opposite end of the actuating frame in position to engage the rod 25 instead of the rod 24.

Various structural modifications may be effected within the spirit and scope of my 130

invention, and I intend only such limitations as are indicated in the appended claims.

What I claim is:

1. A typewriter comprising a platen, a roll to carry duplicating fabric, means for permitting the fabric to advance with a web of paper, and means for holding the roll to permit the web to advance relatively to the duplicating fabric.
2. A typewriting machine comprising means to support a sheet of duplicating fabric extending between the layers of a multi-layer web to advance therewith, and means for locking the duplicating fabric to permit the web to be advanced relatively to the duplicating fabric.
3. A typewriting machine comprising a web guide, a transverse roll rotatable thereon to carry duplicating fabric adapted to extend between the layers of a multi-layer web and to be unwound as the web advances in the machine, means for rotating the roll to wind the fabric thereon, and means for locking the roll to permit the web to be advanced relatively to the duplicating fabric.
4. A typewriting machine comprising a web guide, a transverse roll rotatably supported on the guide near one end to carry duplicating fabric adapted to extend between the folds of a multi-layer web and to be unwound as the web advances in the machine, and means for locking the roll to permit the web to be advanced relatively to the duplicating fabric.
5. A typewriting machine comprising a guide frame having spaced side bars, socket bearings in each of said side bars arranged in offset or staggered relation on opposite sides, rolls having bearings near their respective ends supported in said socket bearings, and adapted to carry duplicating fabric to be introduced between the folds of a multi-layer web and to be unwound as the web advances in the machine, and means for concurrently actuating the rolls to wind the duplicating fabric.
6. A typewriting machine comprising a guide frame having spaced side bars, socket bearings in each of said side bars arranged in offset or staggered relation on opposite sides, rolls having bearings near their respective ends supported in said socket bearings, and adapted to carry duplicating fabric to be introduced between the folds of a multi-layer web and to be unwound as the web advances in the machine, means for concurrently actuating the rolls to wind the duplicating fabric, and means for locking said actuating means to permit the web to be advanced relatively to the duplicating fabric.
7. A typewriting machine comprising a guide frame having spaced side bars, socket bearings in each of said side bars arranged in offset or staggered relation on opposite sides, rolls having bearings near their respective ends supported in said socket bearings, and adapted to carry duplicating fabric to be introduced between the folds of a multi-layer web and to be unwound as the web advances in the machine, means for concurrently actuating the rolls to wind the duplicating fabric, and means for locking said actuating means to permit the web to be advanced relatively to the duplicating fabric.
8. A typewriting machine comprising a guide frame having spaced side bars, socket bearings in each of said side bars arranged in offset or staggered relation on opposite sides, rolls having bearings near their respective ends supported in said socket bearings, and adapted to carry duplicating fabric to be introduced between the folds of a multi-layer web and to be unwound as the web advances in the machine, a gear wheel on each roll, and a single rack frame meshing with the gear wheels and adapted to concurrently actuate the rolls.
9. The combination with a typewriter having a movable carriage and a platen thereon, of a frame connected to the carriage and movable therewith extending backwardly from the body of the machine and having a pair of spaced side bars, a plurality of spindles extending transversely from one of the side bars of the frame and rotatively mounted thereon, means for clamping the inner end of a roll of duplicating fabric on each of the spindles, a gear wheel attached to each spindle, a rack frame meshing with the gear wheels of the several spindles, guide rollers pivotally mounted on the frame and adapted to hold the rack frame in position, and means for locking the rack frame to hold the spindles against rotation, said frame when released being adapted to be moved to concurrently actuate the spindles.
10. A typewriter comprising a platen, a spindle rotatively mounted in the path of a web as it is fed into the machine, means for clamping a duplicating fabric to the spindle, means for turning the spindle to wind the duplicating fabric onto and off of the spindle, and means for locking the spindle to hold the duplicating fabric relative to the web which is being fed into the machine.
11. A typewriting machine comprising a transverse spindle adapted to have duplicating fabric wound thereon, a clamping rod for fastening the inner end of the duplicating fabric roll to the spindle, means for rotatively supporting the spindle at one end, whereby it is adapted to extend between the layers of a multi-layer web, and means for either locking or releasing the spindle to

permit the duplicating fabric to either advance with the web or to be held in position as the web advances.

12. A typewriting machine comprising a frame having side bars, a spindle rotatively mounted on one of the side bars and extending transversely of the frame, and means for clamping the inner edge of a roll of duplicating fabric to the spindle, said spindle and duplicating fabric being adapted to extend between the layers of a multi-layer web and be unwound as the web advances in the machine, and means for actuating the spindle to draw the duplicating fabric and the web backwardly.

13. A typewriting machine comprising a frame having side bars, a spindle rotatively mounted on one of the side bars and extending transversely of the frame, and means for clamping the inner edge of a roll of duplicating fabric to the spindle, said spindle and duplicating fabric being adapted to extend between the layers of a multi-layer web and be unwound as the web advances in the machine, means for actuating the spindle to draw the duplicating fabric and the web backwardly, and means for locking the spindle to permit the web to be advanced relatively to the duplicating fabric.

30 14. A typewriting machine comprising a frame having side bars, a spindle rotatively and removably mounted on one of the side bars and extending transversely of the frame, and means for clamping the inner edge of a roll of duplicating fabric to the spindle, said spindle and duplicating fabric being adapted to extend between the layers of a multi-layer web and be unwound as the web advances in the machine, and means for actuating the spindle to draw the duplicating fabric and the web backwardly.

15. A typewriting machine comprising a frame having side bars, a spindle rotatively and removably mounted on one of the side bars and extending transversely of the frame, and means for clamping the inner edge of a roll of duplicating fabric to the spindle, said spindle and duplicating fabric being adapted to extend between the layers of a multi-layer web and be unwound as the web advances in the machine, means for actuating the spindle to draw the duplicating fabric and the web backwardly, and means for locking the spindle to permit the web to be advanced relatively to the duplicating fabric.

16. A typewriter comprising a platen, a spring adapted to be wound up as the platen advances, a ratchet for holding the platen as it advances step by step, and means for releasing the pawl when the platen has advanced a predetermined distance.

17. A typewriter comprising a platen, a spring adapted to be wound up as the platen

advances, a ratchet for holding the platen 65 as it advances step by step, means for releasing the pawl when the platen has advanced a predetermined distance, and a clutch for releasing the connection between the spring and the platen. 7

18. A typewriter comprising a platen, a spring adapted to be wound up as the platen advances, a ratchet for holding the platen as it advances step by step, and adjustable means for releasing the pawl when the 75 platen has advanced a predetermined distance.

19. A typewriter comprising a platen, a spring adapted to be wound up as the platen advances, a ratchet for holding the platen as 8 it advances step by step, and adjustable means for releasing the pawl when the platen has advanced a predetermined distance, and a clutch for releasing the connection between the spring and the platen. 85

20. A typewriter comprising a platen, a roll adapted to carry duplicating fabric, means for permitting the fabric to advance with a web of paper, a spring adapted to be wound up as the platen advances, a ratchet 90 and pawl for holding the platen as it is advanced step by step, and means for releasing the pawl when the web is advanced a predetermined distance to retract the web, means for actuating the roll of duplicating fabric 95 to retract said fabric.

21. A typewriter comprising a platen, a roll adapted to carry duplicating fabric, means for permitting the fabric to advance with a web of paper, a spring adapted to be 100 wound up as the platen advances, a ratchet and pawl for holding the platen as it is advanced step by step, means for releasing the pawl when the web is advanced a predetermined distance to retract the web, means for 105 actuating the roll of duplicating fabric to retract said fabric, and means for locking the roll of duplicating fabric to permit the web to be advanced relatively thereto.

22. A typewriter comprising a platen, a 110 roll adapted to carry duplicating fabric, means for permitting the fabric to advance with a web of paper, a spring adapted to be wound up as the platen advances, a ratchet and pawl for holding the platen as it is advanced step by step, means for releasing the 115 pawl when the web is advanced a predetermined distance to retract the web, means for actuating the roll of duplicating fabric to retract said fabric, a clutch for releasing the 120 platen from the spring, and means for locking the roll of duplicating fabric to permit the web to be advanced relatively thereto.

23. The combination of a revoluble platen, means for carrying sheets of duplicating 125 material interleaved between plies of web carried around the platen, means for retracting the duplicating material and web

- from the platen, and means for locking the duplicating material against advance while the web is advanced by the rotation of the platen.
- 5 24. The combination with a revoluble platen, of a series of rolls carrying duplicating material and arranged one beyond another at the introductory side of the platen, and means for rotating said rolls simultaneously to wind up the duplicating material thereon.
- 10 25. The combination with a revoluble platen, of a series of rolls carrying duplicating material and arranged one beyond another at the introductory side of the platen, and pinion-and-rack mechanism for rotating said rolls simultaneously.
- 15 26. The combination of a platen, a frame at the introductory side of the platen, and a series of rolls to carry duplicating material, all of said rolls mounted upon said frame, each roll supported at one end only, the other end being free, and the free ends extending in alternate directions.
- 20 27. The combination of a platen, a frame at the introductory side of the platen, a series of rolls to carry duplicating material, all of said rolls mounted upon said frame, each roll supported at one end only, the other end being free, and the free ends extending in alternate directions, and means for winding all of said rolls simultaneously.
- 25 28. In a typewriting machine, the combination with a platen and means for conducting a multiple-ply web through the machine and over the platen, of a set of rolls mounted to occupy positions between different plies of the web, said rolls carrying sheets of duplicating material, and means for winding the duplicating material upon the rolls.
- 30 29. In a typewriting machine, the combination with a platen and means for conducting a multiple-ply web through the machine and over the platen, of a set of rolls mounted to occupy positions between different plies of the web, said rolls carrying sheets of duplicating material, and means for winding the duplicating material upon the rolls, provision being also made for effecting a longitudinal adjustment of the web, to bring a fresh section thereof into use, while the sheets of duplicating material remain stationary.
- 35 30. In a typewriting machine, the combination with a platen and means for conducting a multiple-ply web through the machine and over the platen, of a set of rolls mounted to occupy positions between different plies of the web, said rolls carrying sheets of duplicating material, and means for winding the duplicating material upon the rolls during a longitudinal travel of the web in the same direction as the duplicating material.
- 40 31. In a typewriting machine, the combination with a platen and means for conducting a multiple-ply web through the machine and over the platen, of a set of rolls mounted to occupy positions between different plies of the web, said rolls carrying sheets of duplicating material, and means for winding the duplicating material upon the rolls during a longitudinal travel of the web in the same direction as the duplicating material, provision being made for effecting a longitudinal adjustment of the web in the opposite direction while the rolls remain stationary.
- 45 32. The combination with a revoluble platen and means to guide a multiple-ply web in a tortuous course through the machine and around said platen, of means for supporting duplicating sheets between the plies of said web, means for enabling the duplicating sheets to be withdrawn from said tortuous course during a movement of the web in the same direction, and means to detain the duplicating sheets while the web is adjusted longitudinally in the opposite direction to bring fresh areas thereof into contact with the duplicating sheets.
- 50 33. In a typewriting machine, the combination of a platen, means for guiding a multiple-ply web through the machine, a series of rolls to carry duplicating material, and means to connect said rolls for a simultaneous winding movement.
- 55 34. In a typewriting machine, the combination of a platen, means for guiding a fan-fold work-web through the machine and over the platen, and transverse rolls mounted one behind another at the introductory side of the platen and each supported at only one end, said rolls extending at their free ends in alternate directions.
- 60 35. In a typewriting machine, the combination of a platen, means for guiding a fan-fold work-web through the machine and over the platen, transverse rolls mounted one behind another at the introductory side of the platen and each supported at only one end, said rolls extending at their free ends in alternate directions, and means to rotate said rolls simultaneously.
- 65 36. The combination with a revoluble platen and means to guide a multiple-ply web around the same, of a series of rolls to carry sheets of duplicating material, said rolls rotatable during a traveling movement of the web in the same direction, to clear the duplicating sheets of the platen sufficiently to permit a longitudinal adjustment of the web in the opposite direction while the duplicating material remains stationary.
- 70 37. The combination with a revoluble platen and means to guide a multiple-ply web around the same, of a series of rolls to carry sheets of duplicating material, said
- 75 80 85 90 95 100 105 110 115 120 125

rolls rotatable during a traveling movement of the web in the same direction, to clear the duplicating sheets of the platen sufficiently to permit a longitudinal adjustment 5 of the web in the opposite direction while the duplicating material remains stationary,

and means for mechanically holding the duplicating sheets stationary during such adjustment of the web.

In witness whereof, I have hereunto set 10 my hand this 26th day of January, 1917.

RICHARD D. ANANSON.
